(57) **CLAIM**

The ornamental design for a plug assembly for transmission line, as shown and described.

DESCRIPTION

FIG. 1 is a perspective view of a plug assembly for transmission line showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof.

FIG. 8 is a perspective view thereof, in use condition; and,

FIG. 9 is another perspective view thereof, in use condition.
